UNITED STATES PATENT OFFICE.

ARTHUR ATWATER KENT, OF PHILADELPHIA, PENNSYLVANIA.

ELECTRIC CONTACT DEVICE.

978,030.

Specification of Letters Patent.

Patented Dec. 6, 1910.

Application filed August 16, 1905. Serial No. 274,361.

To all whom it may concern:

Be it known that I, ARTHUR ATWATER KENT, a citizen of the United States, residing in the city and county of Philadelphia, 5 State of Pennsylvania, have invented a new and useful Electric Contact Device, of which the following is a specification.

In gas engine work and in many other places where an electric circuit must be 10 rapidly made and broken, speed, reliability and uniformity of this circuit closing and breaking mechanism are quite important. In obtaining these advantages, I have produced a novel construction of a circuit controller or timer, which is adapted for both 15 a jump and a make and break spark and in which the contact is both made and broken by a single snap of a spring and the time of contact is the same for all speeds of the 20 engine.

A further object of my invention is to eliminate the speed of the engine as a factor in determining the time of contact duration.

25 In my novel construction a spring is brought to tension by the revolution of the engine and the contact is not made until the spring is released so that the time of contact is independent of the speed of the 30 engine and depends primarily upon the speed of return of the spring to its original position.

It further consists of other novel features of construction all as will be hereinafter 35 fully set forth.

Figure 1 represents a front elevation of an electric contact device embodying my invention. Fig. 2 represents a side elevation thereof showing the initial position of 40 the parts. Fig. 3 represents a side elevation similar to Fig. 2 but showing the position the parts assume on the further revolution of the cam employed. Fig. 4 represents a side elevation similar to Fig. 2 showing the 45 position the parts assume after the roller has been released and is moving back to its original position. Fig. 5 represents an application of my invention adapted for a make and break spark inside the cylinder. 50 Fig. 6 represents a sectional view on line x—x, Fig. 5. Fig. 7 represents another embodiment of my invention, in side elevation.

Similar numerals of reference indicate corresponding parts in the figures.

55 Referring to the drawings: 1 designates

a shaft suitably journaled and having fixedly mounted thereon a disk or plate 2 having an operative cam surface 3, the latter being made up of a preferably nearly radial leading face 15, a top 16 and a release 60 face 17. 4 designates a stationary cam loosely mounted on said shaft, said cam being composed of a preferably non-radial curved face 18, operating in conjunction with the face 15 as a wedge, an intermediate 65 portion 19 and a seat or stop 20, against which the roller normally rests.

5 designates a roller or pin which constitutes the actuating member of my device and which is held in its normal position in 70 conjunction with the face 20 of the cam 4 by means of springs 6 secured to the ends thereof, the other ends of said springs being suitably secured to any fixed point 7 which is located in such a position that the tendency of the springs 6 is to cause the roller 5 to be retracted over the faces 16 and 17 to its initial position against the seat or stop 20.

8 designates the circuit closing member 80 which comprises the movable contact point support and is preferably a resilient arm suitably secured at one end to any desired point and at the other end provided with a cam face 9 having the front face 10, the 85 bottom face 11 and the release face 12.

13 designates a movable contact point on the spring 8, preferably of platinum and 14 designates a stationary pin or screw with which it makes contact, which in the present 90 instance consists of an adjustable screw provided with a platinum or other tip, it being evident that the screw itself may be made of any suitable conducting material.

21 designates a conductor leading to the screw 14 and 22 designates a conductor from the other end of the circuit to the arm 8.

The operation is as follows:—As the cam 2, which is fixed on the shaft 1 revolves, its face 15 initially engages the roller 5 and moves said roller forwardly along the face 19 of the stationary cam 4 against the tension of the springs 6. When the roller 5 reaches the inclined face 18 of the fixed cam 4 the roller will travel outwardly until it passes beyond the face 15, as indicated in Fig. 3, whereupon the springs 6 will cause said roller to be quickly retracted, said roller moving along the face 16 of the movable cam until it engages the face 10 upon 100 105 110

the arm 8. The roller will then come into operative engagement with and force the face end 10 of the cam 9 outwardly and cause a contact to be made between the point 14 and the arm at 13, which contact will be maintained during the extremely short time taken by the roller in passing the face 11. Owing to the construction of the cam 9, it will be apparent that the contact will be quickly made and broken. On the further revolution of the cam 2, the cam 3 will engage the roller 5 and the operation will be repeated. While I have shown the stationary cam as being mounted on the revolving shaft, it is apparent that this can be suitably secured to any convenient support and that the result will be the same. By varying the operative surface of the cam face 9 the duration of the contact may be increased or diminished as desired. By slightly changing the contour of the faces 10 and 12 so that the same incline downwardly in the form of a V-shape, it will be readily apparent that the contact will be almost instantaneously made and broken while if the lower surface of said cam is faced off the duration of the contact will be increased. It is apparent that the contact in my novel construction is not made until the spring is released and it will be readily understood by those skilled in the art that the time of contact will be limited to the time which is necessary for the roller to travel from the point at which it is released to its initial position and is practically independent of the speed of the engine. It will also be apparent that the roller or actuating member —5— by being advanced by the cam —3— and returned by the spring —6— is given a substantially reciprocatory movement although the cam itself has a rotary movement, and that on the return movement of the member —5— it is displaced or forced laterally or transversely from the path of its advanced movement by the cam surface —18— and the face —16— of the cam —3— into a position such that it returns into a slightly different path from that in which it was advanced to bring it into engagement with the circuit closing member and that its speed on its return movement is constant; that is to say, the time which lapses from its release to its return to its original position is constant irrespective of the speed of the advancing means, and that inasmuch as the spring preferably exerts considerable tension, comparatively speaking, upon the member —5— its return movement is practically instantaneous. I employ an inclined face 17 on the cam 3 for the reason that if the engine kicks backwardly the roller 5 will be wedged outwardly thus preventing any breakage of the mechanism and it will also be noted that if this occurs the roller will not produce a contact.

In the embodiment shown in Fig. 5 the device is shown as being adapted for a make and break spark. The arm 8 is secured at one end to a rock shaft 23 which is provided with an arm 24 at the end of which is the contact, said shaft 23 being journaled in a bearing 25 in the cylinder 26. 27 designates a stationary contact which is insulated from the cylinder as at 28 and provided with a suitable connection 29. 30 designates the ground connection which is connected with the cylinder at any suitable point. As the spring arm 8 is actuated by the cams, the shaft 23 will be rocked and the contact on the arm 24 will engage the stationary contact 27 and make a contact.

In the embodiment shown in Fig. 7, 31 designates a cam mounted on a shaft 32 and having an operative cam surface 33 provided with a leading face 34 and an inclined face 35. 36 designates a lever arm pivoted at 37 and one end of which is adapted to be engaged by the cam 33. 38 designates an arm pivoted at 39 to the other end of the lever 36. 40 designates a spring secured to the arm 36 and engaging a pin 41 on the arm 38 whereby said arm 38 is normally retained in alignment with the arm 36. 42 designates a bevel at the end of the arm 38. 43 designates a spring arm suitably supported and having secured thereto a contact 44 adapted to coact with a contact 45, the end of said arm engaging the beveled end of the arm 38 during the operation. 46 designates a stop for the spring arm 43. 47 designates a tension spring for the arm 36.

The operation will be as follows: As the cam 32 revolves the leading face 34 of the cam 33 will engage the end of the lever 36 and cause said lever to be turned on its pivotal point 37 which will cause the other end of said arm 36 to be moved downwardly. The arm 38 which is hinged at 39 will be moved only slightly downward but will turn on its hinge 39 and the bevel 42 will pass under the end of the arm 43, it being understood that the tension of the spring 43 is normally in the direction of the stop 46 which prevents the arm 43 from being moved downwardly by the arm 38. As the arm 36 returns to its initial position, due to the spring 47, the end of the arm 38 will engage the end of the spring 43 and cause said spring to be moved upwardly and the contact 44 will engage the other contact 45 thus completing the circuit, it being seen that, owing to the point at which the arm 38 is hinged, said arm will be substantially in alignment with the arm 36 as said arm 36 returns to its normal position.

It will be noted that in my novel construction the contact is made positively and that I do not rely upon momentum. I wish to call special attention to the movement of the pin or wedging device 5 since the same

does not move rearwardly over the same path in which it is brought to tension and this wedging device on its return movement both makes and breaks the contact. This 5 provides a certain and positive operation of the circuit closing member. The movable member 5 operates between two fixed points located at each end of its path of movement. It normally rests against the shoulder or 10 stop 20 but is intermittently moved to the opposite end of its path against the shoulder 18 by which it is released. This movable member 5 contacts or engages with the circuit closing member or support 8 intermediate of the ends of its path of movement, or, in other words, intermediate the points 15 between which it is moved by the cam or moving member 2.

I have deemed it unnecessary to show and 20 describe various details or accessories adapted to co-act with my invention, as the construction of the same will be apparent to those skilled in the art and they form, *per se*, no part of my present invention. It will 25 be further apparent that the manner of supporting and assembling the springs 6 with respect to the pin 5 and the manner of supporting the arm 8 and its adjuncts may be varied according to requirements and 30 I may also vary the contour of the various cam faces according to the exigencies of the case without departing from the spirit of my invention and I do not therefore desire to be limited in every instance to the exact 35 construction herein shown and described.

Having thus described my invention, what I claim as new and desire to secure by Letters Patent, is:—

1. In a contact device, a movable member, 40 a tension device therefor, a stop for limiting the movement of said member in one direction, means for advancing said member to increase the tension thereon, separate means for releasing said member, and a contact

5 member disconnected from and co-acting with said movable member on its return movement to both make and break the circuit.

2. In a contact device, the combination of 50 a movable member, a tension device therefor, a movable cam for advancing said member, and acting in conjunction with a stationary cam to effect the release and return of said member and means disconnected from said member and co-acting therewith on the return movement of said member to both make and break the circuit.

3. In a contact device the combination of 60 a movable member, a tension device therefor, means for advancing said member, separate means for effecting the release and return of said member in a different path from that in which it was advanced and means co-acting with said member on the return movement thereof to both make and break the 65 circuit.

4. In a contact device, the combination of a movable member, a tension device therefor, means for advancing said member, separate means for effecting the release and return of said member, and a spring contact arm independent of and disconnected from said movable member and co-acting therewith on the return movement of said member to both make and break the circuit before said member reaches its initial position. 70

5. In a contact device, a movable member, a stop for limiting the movement of said member in one direction, means for advancing said member, means for returning said member to said stop in a different path from 80 that in which it was advanced, and a contact member disconnected from and co-acting with said movable member on its return movement and intermediate the points between which it was advanced to both make 85 and break the circuit.

6. In a contact device, a movable member, a tension device therefor, a stop for limiting the movement of said member in one direction, means for advancing said member to 90 increase the tension thereon, separate means for releasing said member, said member returning to the stop in a different path from that in which it was advanced, and a contact member disconnected from and co-acting 95 with said movable member on its return movement to both make and break the circuit.

7. In a contact device, the combination of a movable member, a tension device therefor, 100 means for advancing said member, a resilient contact arm independent of said movable member, means disconnected from said arm for effecting the release and return of said member, and means carried by said arm 105 and co-acting with said member on its return movement to cause said arm to hold the circuit closed for a definite uniform length of time and to then break the circuit.

8. In a contact device, the combination of a movable member, a tension device therefor, means for advancing said member, a resilient contact arm independent of said movable member, means engaged by said movable member for effecting the release of said member, said member returning in a different path from that in which it was advanced, and a stationary contact co-acting with the contact on said contact arm on the return 115 movement of said movable member to both make and break the circuit.

9. In a contact device the combination of a movable member, a tension device therefor, means for advancing said member, separate means engaged by said movable member for effecting the release of the same, means to force said member on its return into a path different from that in which it was advanced, and means disconnected from said member and co-acting therewith on the re- 125

turn movement of said member to hold the circuit closed for a definite length of time and then to break the circuit.

10. In a contact device, a movable member, a tension device therefor, a movable cam member co-acting with said movable member for bringing the same to tension, a stationary cam for effecting the release of said movable member, and a contact member 10 with which said movable member co-acts to make and break the circuit on the return movement of the latter.

11. In a contact device, a movable member, a tension device therefor, a stationary 15 releasing member with which the movable member co-acts, a movable cam member having a leading face, top face and release face, said movable cam member co-acting with the movable member and the stationary release 20 member to effect the release and return of said movable member, the latter being in the path of the leading face of the movable cam member, and a contact member coacting with said movable member on its return 25 movement to both make and break the circuit.

12. In a contact device, a movable member, a tension device therefor, a stationary member having a non-radial cam face there- 30 on with which the movable member coacts, a movable cam member co-acting with said movable member and said non-radial cam face to effect the release and return of said movable member in a different path from 35 that in which it was advanced, and a contact member with which said movable member co-acts on its return movement to cause a contact to be both made and broken.

13. In a contact device a movable member 40 and a tension device therefor, means for advancing said member, separate means engaged by said movable member for effecting the release of the same, means for guiding said movable member on its return in a path 45 different from that in which it was advanced, a second movable member co-acting with the return movement of said first movable member, a contact carried by said second member, and a second contact with 50 which said first contact co-acts to make and break the circuit.

14. In a contact device, a movable member, a tension device therefor, means for advancing said member, separate means for 55 effecting the release and return of said member in a different path from that in which it was advanced, a second movable member co-acting with the return of said first movable member, a contact carried by said sec- 60 ond member, a stationary contact co-acting therewith to make and break the circuit, and means for preventing a contact being made if the means for advancing said movable member travels in a reverse direction.

65 15. In a contact device, a movable mem-

ber, a tension device therefor, means for advancing said member, separate means for effecting the release and return of said member, a second movable member co-acting with the return of said first movable member, a contact carried by said second member, a stationary contact co-acting therewith to make and break the circuit, and means for preventing a contact being made if the means for advancing said movable member travels in a reverse direction.

16. In a contact device, a movable member, a tension device therefor, a movable cam for advancing said member, separate means for effecting the release of said member, a stop for said member, an adjustable stationary contact, and a movable contact carrying member coacting therewith to make and break the circuit on the return movement of said movable member, said movable cam 85 when moved in a reverse direction coacting with said movable member and said stop to prevent a contact being made.

17. In a contact device, a movable member, a tension device therefor, means for advancing said member, separate means for effecting the release of said member, means disconnected from and coacting with the movable member on its return movement to cause a contact to be both made and broken, 95 and means for preventing said movable member engaging with said contact forming means when the advancing means travels in a reverse direction.

18. In a contact device, a movable member, a tension device therefor, a stop for limiting the movement of said member in one direction, means for advancing said member to increase the tension thereon, separate means for releasing said member, and means for preventing said movable member engaging with said contact member when the advancing means for said member travels in a reverse direction.

19. In a contact device, a movable member, a tension device therefor, an advancing member to advance said movable member against said tension device, means engaged by said movable member for releasing the same to allow it to return in a reverse direction to the movement of said advancing member, and a contact member disconnected from and coacting with the return movement of said first movable member to both make and break the circuit.

20. In a contact device a movable member and a tension device therefor, a rotating advancing member, means for effecting the release of said movable member, means for guiding said movable member on its return movement in a path different from that in which it was advanced and in a reversed direction to the rotation of the rotating advancing member, and a contact member disconnected from and co-acting with the re- 130

turn movement of said movable member to both make and break the circuit.

21. In a contact device, a movable member, a tension device therefor, means for increasing the tension on said member by a displacement thereof, and separate means engaged by said member for releasing the same from said tension increasing means.

22. In a contact device the combination of a movable member, a tension device therefor, a cam adapted to advance said member, separate means engaged by said member for effecting a release and return of the same, and means positively operated by the return movement of said member to first close and then open a circuit.

23. In a contact device the combination of a stationary member, a movable member, a tension device therefor, and means for advancing said movable member, said advancing means acting in conjunction with said stationary member to effect the release and return of the said movable member.

24. In a contact device the combination of a relatively stationary member, a relatively movable member, a tension device therefor, means for advancing said movable member, said advancing means acting in conjunction with said stationary member to effect the release and return of the said movable member, and means positively operated by the movable member on its return movement for first holding a circuit closed for a uniform length of time and then breaking said circuit.

25. In a contact device the combination of a movable member under tension, a stop for limiting the movement of said member in one direction, means for advancing said member against the action of said tension, separate means for releasing said member from said advancing means, and means to cause said member to return to said stop in a different path from that in which it was advanced.

26. In a contact device the combination of a movable member under tension, a stop for limiting the movement of said member in one direction, means for bodily advancing said member against the action of said tension, means to cause said member to return to said stop in a different path from that in which it was advanced, and means positively operated by said movable member on its return movement for first holding a circuit closed for a definite length of time, and then to rapidly break said circuit.

27. In a contact device the combination of a movable member, means for advancing said member, means for returning said member, and means intermediate of the points between which said movable member is actually moved by said advancing means and operated by said movable member on its return movement, to both make and break a circuit.

28. In a contact device a contact member, a movable member normally at one end of its path, means for advancing said member to the opposite end of its path, means for returning said member to its original position, and for positively forcing said member during its return movement into and out of engagement with said contact member intermediate the points between which it is moved by said advancing means.

29. In a contact device, a movable member normally at one end of its path, means to advance said member to the opposite end of its path and means operatively engaged by said member on its return movement and intermediate the points between which it is moved by said advancing means to open and close a circuit.

30. In a contact device, a movable member adapted to be moved between two points and normally located at one of said points, a contact member situated between said points, means to move said movable member from one point to the other without operating said contact device and means to cause said member to operate said contact member on its return movement to make and break the circuit.

31. In a contact device a movable contact arm, a movable member under tension and normally at one end of its path, means for moving said member to the opposite end of its path, means for returning said member to its original position, and means for laterally displacing said member during its return movement and intermediate the ends of its path into and out of contact with said contact arm.

32. In a contact device a yielding contact arm, a movable member normally at one end of its path, means for advancing said member at a variable speed, separate means cooperating with said advancing means for releasing said member, means for returning said member when released to its original position and at a uniform rate of speed, and means to positively move said movable member into operative engagement with said yielding contact arm intermediate the point of its release and its original position.

33. In a contact device a movable contact arm, a movable member under tension normally at one end of its path, means for moving said member to the opposite end of its path against the action of said tension, and means to positively move said movable member when released into and out of contact with said movable arm intermediate the points between which it is moved by said first mentioned means.

34. In a contact device a movable member normally held under tension against a stop, means to move said member away from said stop to increase the tension thereon, separate means to release said member to allow said

- tension to return it to said stop, and a contact arm positively engaged and moved by said member on its return movement and before the same engages said stop.
35. In a contact device, a contact arm, a movable member, means to advance said member in one direction, independent means to return it to its original position in a uniform length of time and means to laterally displace said member to force the same into engagement with said contact arm and before said member reaches its original position.
36. In a contact device, a contact member, a movable member under tension normally at one end of its path, advancing means for moving said movable member to the opposite end of its path against the action of said tension, and means to positively move said movable member when released into and out of operative engagement with said contact member intermediate the points between which it is actually moved by said advancing means.
37. In a contact device, a contact member, a movable member under tension normally at one end of its path, means for moving said movable member to the opposite end of its path means for returning said member to its original position and means for laterally displacing said member during its return movement and intermediate the ends of its path into and out of operative engagement with said contact member.
38. A movable member normally situated at one extreme end of its path, means to move said member to the opposite end of its path and means engaged by said member on its return movement and intermediate the points between which it is moved by said moving means for making and breaking a circuit.
39. In a contact device a contact member a movable member normally situated at one end of its path, means to give said movable member a substantially reciprocatory movement and means engaged by said movable member on its movement in one direction and intermediate the points between which it is actually moved by said first mentioned means to close and open a circuit.
40. A movable member normally situated at one end of its path, means to advance said member to the other end of its path and means operated by said member on its return movement and intermediate the points between which it is moved by said advancing member for making and breaking a circuit.
41. In a contact device a contact member, a movable member under tension normally at one end of its path, means for moving said member to the opposite end of its path against the action of said tension and means to move said movable member into and out of operative engagement with said contact member intermediate the points between which it is moved by said first mentioned means.
42. In a contact device, a reciprocatory member, a circuit closing member adapted to be operated by said reciprocatory member at a predetermined point intermediate the ends of the path of said reciprocatory member, and means to cause said reciprocatory member to traverse that portion of its path in which it operates said circuit closing member in a substantially constant interval of time irrespective of the speed at which said reciprocatory member traverses other portions of its path.
43. In a contact device a reciprocatory member, and a circuit closing member adapted to be engaged by said reciprocatory member at a pre-determined point intermediate the ends of the path of said reciprocatory member, and means to cause said reciprocatory member to traverse that portion of its path in which it engages said circuit closing member at a substantially instantaneous speed irrespective of the speed at which said reciprocatory member traverses the other portions of its path.
44. In a contact device a movable circuit closing member and an actuating member under tension normally at one end of its path, means for moving said actuating member to the other end of its path and for returning it to its original position, and means for laterally displacing said actuating member during its return movement and intermediate the ends of its path into and out of operative engagement with said circuit closing member.
45. In a contact device a stationary contact point, driving means, a movable contact point, and a support therefor, a reciprocatory actuating means and means to move said actuating means in a slightly looped path to momentarily bring said contact points into engagement with each other.
46. In a contact device the combination of a movable member, a stop against which said member is normally held, means to advance said member, means to return said member against said stop in a substantially constant interval of time, and a circuit closing member operatively engaged and moved by said movable member on its return movement and before the return of said member to said stop.
